Meyers, Cushman & Co.

UNITED STATES PATENT OFFICE.

INGENUIN HECHENBLEIKNER, OF CHARLOTTE, NORTH CAROLINA, ASSIGNOR TO SOUTHERN ELECTRO-CHEMICAL COMPANY, OF NEW YORK, N. Y., A CORPORATION OF NEW JERSEY.

CONCENTRATING APPARATUS.

1,264,509.

Specification of Letters Patent. Patented Apr. 30, 1918.

Application filed November 6, 1914. Serial No. 870,624.

To all whom it may concern:

Be it known that I, INGENUIN HECHENBLEIKNER, a subject of the Emperor of Austria, residing at Charlotte, in the county of 5 Mecklenburg and State of North Carolina, have invented new and useful Improvements in Concentrating Apparatus, of which the following is a specification.

This invention relates to the concentration 10 of acids and the invention is described hereinafter by way of illustration as applied to the concentration of dilute sulfuric acid for which purpose I have employed this invention to concentrate the acid to a 98% purity.

15 A principal object of the invention is to provide a very efficient apparatus for effecting the concentration of a weak acid.

A further object of the invention is to provide for effecting the concentration of 20 the acid with as little loss as possible in the quantity or mass of acid which is being concentrated.

25 A further object of the invention is to prevent, as far as possible, losses in heat employed in carrying out the operation.

The invention resides in the apparatus to be described more fully hereinafter.

The invention consists in those features of 30 the apparatus hereinafter described all of which contribute to produce an efficient apparatus for concentrating acids.

A preferred embodiment of my invention will be particularly described in the following specification while the broad scope of 35 my invention will be pointed out in the appended claims.

In the drawing which illustrates a preferred embodiment of my invention,—

40 Figure 1 is a vertical section through the apparatus of my invention and which I prefer to use in practising my novel method.

Fig. 2 is a plan of the apparatus shown in Fig. 1.

45 Referring more particularly to the parts, 10 represents any suitable means for maintaining a bath 8 of the acid which is to be concentrated. This means is preferably in the form illustrated and constructed of a suitable material which resists the action of 50 the acid. I prefer to provide this holder or retort with a sheathing 9 of lead or similar material which resists the acid, and construct the wall of a material or lining of suitable brick which also resists the action 55 of the acid.

The lower portion of the basin is preferably laterally extended and directly over this basin I prefer to form the concentrator into a tower 10^b and in this tower I prefer to provide a packing 11 of open checker-work which forms an obstruction in the path of the liquid acid which I prefer to admit through inlet pipes 12 in the cover 13 of the concentrator. This checker-work 11 is preferably supported on suitable arches 14 of 60 brick or other material which will resist the acid. The lower parts of these arches are cut away so as to form gaps 14^a by means of which the entire interior of the basin is made to connect with an outlet valve 25^a by 65 means of which the basin may be cleaned when desired.

In order to concentrate the acid I prefer to remove the volatile impurities in the acid without raising the temperature of the bath 75 to the boiling point. In this way, I effect the concentration without substantial loss in the quantity of acid. This is preferably effected through the medium of a heated gas which is preferably heated to a relatively high temperature such as will permit 80 of the gas passing through the bath in order to take up the water or other volatile impurities so that the hot gas issues from the bath at a temperature below the boiling 85 point of the bath. In this way although I am utilizing the highly efficient high temperature of the gas this does not have the effect of carrying off the acid but substantially eliminates the water or similar impurities. 90

For this purpose, I prefer to provide a blower or fan 1 which draws in atmospheric air and forces the same through a pipe 2 and regulating valve 3 into a branch pipe 4, which branch pipe preferably connects 95 with two mains or distributing manifolds 5 which are preferably disposed on opposite sides of the concentrator.

I prefer to provide means for heating the air to about 400° in these manifolds, for 100 which purpose I prefer to provide oil burners 6 which are preferably arranged in the ends of the manifolds 5 and which are also preferably of the atomizer type and therefore provided with air pipes 26 which lead 105 off from the main air pipe connection 2. These burners are supplied with fuel through suitable pipes 25. The manifolds or mains 5 are preferably lined with fire brick and covered with a suitable sheathing. In order 110

to conduct the hot air or other gas from the manifolds 5 through the bath, I prefer to provide a plurality of inclined twyers 7 which lead downwardly from the manifolds 5 so that their mouths are disposed below the level of the bath and as indicated these mouths are preferably disposed in a horizontal plane so that the air will pass out of the mouth at all points around its periphery. 10 In this way, I effect a thorough distribution of the hot air or gas in passing through the bath.

The gases as delivered to the bath are substantially at 400° centigrade and the arrangement is such that they pass from the bath at about 200° centigrade. As the gases pass from the bath, they pass upwardly through the checker-work 11 which forms a baffle for the gases and as the gases pass upwardly they come in contact with weak acid which is admitted through the inlets 12 so as to fall down in a finely divided state, that is, the liquid will trickle down in a descending current coming in contact with the hot gases passing upwardly. In this way, I cause the incoming weak acid to absorb a large portion of the heat of the gases which are passing out of the concentrator and I thereby effect a very substantial economy. 20

30 In order to remove any acid which may still remain in the gases which pass from the tower through the pipe 15, I prefer to provide a filter 16 which is built of acid resisting material and filled with a finely divided acid resisting substance 17, said substance being supported preferably on suitable arches 18, also of acid resisting bricks or similar material. The gases pass downwardly through this mass or material 17 and the moisture and acid carried in the gases are deposited and eventually drip down into the basin 19 at the bottom of the filter from which this very weak acid can be drawn off through a suitable valve 21. The outlet at this point is air-sealed in any suitable manner, such as that indicated in Fig. 1. The waste gases pass from this filter near the base through a suitable pipe 20 which directs the same upwardly.

40 50 In order to enable the manifolds 5 to be cleaned when desired, their upper sides are provided with removable covers 27. The concentrated acid is delivered through a sealed overflow 22 into a cooler 23 which cooler may be cooled by means of a suitable coil 23^a, through which brine or other cooling medium may be circulated. From the cooler the concentrated acid may be drawn off through a suitable valve 24. All parts 55 which come in contact with the acid should be of acid resisting material.

It is understood that the embodiment of the invention described herein is only one of the many embodiments or forms the invention may take and I do not wish to be

limited in the practice of the invention nor in my claims to the particular embodiment set forth.

What I claim is:

1. In an apparatus for concentrating acid, 70 the combination with a container for maintaining a bath of the acid to be concentrated, means for conducting a hot gas in a plurality of separated streams into the bath at a point below the surface of the latter for absorbing and carrying off the volatile impurities in the bath, means for admitting a current of weak acid to the bath from a point above the container to replenish said bath, and means for heating the incoming current 80 of acid by the gas escaping from the bath.

2. In an apparatus for concentrating acids, the combination with a container for holding a bath of the acid to be concentrated, means for introducing a hot gas into the bath at a 85 point below the surface of the latter, said means including a blower, a distributing main connected with the blower and communicating with the container and a heater connected with the main, the said gas passing through the bath to absorb and carry off the volatile impurities therein, means for admitting a current of acid to the bath to replenish the same, means for heating the incoming current of acid by the gas escaping 90 from said bath, and means for subsequently filtering the gas.

3. In an apparatus for concentrating acids, the combination with a container for holding a bath of the acid to be concentrated, 100 means for passing a hot gas through said bath in a plurality of separated streams to absorb and carry off the volatile impurities therein, said means including a blower, a distributing main connected with the blower, 105 a plurality of separated pipes leading from said main and a heater connected with the main, a checker work baffle arranged over said bath and through which baffle the hot gas passes upwardly from the bath, and 110 means for admitting a current of weak acid so as to descend through said checker work to the bath to absorb the heat of the gases ascending through said checker work baffle.

4. In an apparatus for concentrating acids, 115 the combination with a container for holding a bath of the acid to be concentrated, means for introducing a gas to said bath in a plurality of separated streams at a point below the surface of the latter, said gas 120 passing through the bath to absorb and carry off the volatile impurities therein.

5. In a concentrating apparatus, the combination with a container for holding the material to be concentrated, an arch arranged in the container, a chamber section extending upward from the container, a baffle located in the chamber section, a gas conducting tube leading from the upper end of the chamber, a gas main located adjacent 130

the container, and means for conducting the gas from the gas main and introducing the same into the bath at a point below the surface of the latter.

5. 6. In a concentrating apparatus, the combination with a container for holding a bath of the material to be concentrated, a chamber extending upward from the container, a checker work baffle located in said chamber, a gas conduit leading from the upper end of the chamber, a gas main and a plurality of pipes leading from the gas main to the container and adapted to introduce gas in separated streams from the gas main 10 to the bath in the container.

7. In a concentrating apparatus, the combination of a container for holding a bath of the material to be concentrated, a chamber extending upward from the container, a baffle arranged within said chamber, a gas conduit leading from the upper end of the chamber, a filter connected with said gas conduit, and means, including a distributing main and a plurality of spaced pipes connected with said main and discharging into the bath below the surface of the latter, for passing a gas through the bath in the container.

8. In a concentrating apparatus, the combination with a container for holding a bath of the material to be concentrated, a

chamber extending upward from the container, a checker work baffle located in said chamber, a pair of gas mains located at opposite sides of the container, gas conducting pipes leading from the gas main through the container and having their discharge ends adapted to project below the surface of the bath of the material in the container whereby to pass a gas through said bath, 40 and a gas conduit leading from the upper end of the chamber.

9. In a concentrating apparatus, the combination with a container for holding a bath of the material to be concentrated, a chamber extending upward from said container, gas mains located at opposite sides of the container downwardly inclined, gas conducting pipes leading from the mains and adapted to discharge gas into the bath at a point 50 below the surface of the latter, means for introducing a heated gas under pressure into said gas mains, a baffling device located within the chamber, and a gas conduit leading from the upper end of the chamber. 55

In testimony whereof I have hereunto set my hand in presence of two subscribing witnesses.

INGENIEUR HECHENBLEIKNER.
